(57) **CLAIM**

The ornamental design for collapsible and touch keyboard with a holder, as shown and described.

DESCRIPTION

FIG. 1 is a front perspective view of a collapsible and touch keyboard with a holder showing our new design;

FIG. 2 is a rear perspective view thereof;

FIG. 3 is a front elevational view thereof;

FIG. 4 is a rear elevational view thereof;

FIG. 5 is a left side elevational view thereof the right side being a mirror image;

FIG. 6 is a top plan view thereof;

FIG. 7 is a bottom plan view thereof;

FIG. 8 is a front perspective view thereof shown folded;

FIG. 9 is a rear perspective view thereof;

FIG. 10 is a front elevational view thereof;

FIG. 11 is a rear elevational view thereof;

(Continued)

FIG. 12 is a left side elevational view thereof the right side being a mirror image;

FIG. 13 is a top plan thereof; and,

FIG. 14 is a bottom plan view thereof.

1 Claim, 14 Drawing Sheets
